UNITED STATES PATENT OFFICE

GEORGE H. CAMPBELL, OF TORONTO, ONTARIO, CANADA.

PROCESS OF PREPARING FLAX.

1,086,272.

Specification of Letters Patent.

Patented Feb. 3, 1914.

No Drawing.

Application filed March 11, 1910. Serial No. 548,701.

To all whom it may concern:

Be it known that I, GEORGE H. CAMPBELL, a citizen of Canada, and a resident of Toronto, in the county of York and Province 5 of Ontario, Canada, have invented certain new and useful Improvements in Processes of Preparing Flax, of which the following is a specification.

This invention relates to the preparation 10 of flax for the various purposes of the textile industry, and has in view a quicker and more economical treatment, and which will produce a greater yield than previously existing processes, all as now will be explained, 15 reference being had to the following specification and claims. In carrying out this operation, flax stalks or straw in a dry state, are passed through a breaking machine, which removes the larger portion of the 20 various incrusting matters or shives, the diminution in weight of the straw treated being about forty-five per cent. of the total original weight.

To render the stalks sufficiently dry they 25 may either be air-dried or dried by the application of heat, the stalks being for this purpose placed on suitable shelves or frames, below which are placed pipes through which passes hot water or steam, heated to a mod- 30 erate temperature.

After the stalks have been passed through the breaking machine, which may be of any ordinary and well-known kind, they will still contain a considerable proportion of 35 gummy, ligneous and other incrusting matters. For most uses the fiber requires further treatment to remove the larger portion, or all, of this shive material adhering to the fiber. This is done by a process of ret- 40 ting, which will now be described and which may be applied either immediately after the stalks come from the breaking machine or after the fiber has been subjected to the various usual operations of scutching, hawking, 45 spinning and weaving. In each of these various operations, tending to convert the broken stalks into yarn or cloth, the material progressively loses a certain amount of adhering incrusting material or shives, 50 but not all.

To make a more complete removal of the shives, the fiber, after any of the above mechanical treatments, has to be subjected to a process of retting. There are three classes 55 of retting processes used, namely: field retting or dew retting, water retting, and

chemical retting. The retting process that will now be described belongs to the last class, or retting by means of a solution of one or more chemicals.

By breaking the flax before retting it becomes particularly well adapted to chemical retting, owing to the readiness with which solutions containing chemical agents come in contact with every portion of the gummy, 60 ligneous and other incrusting matter attached to the fiber. Especially is such the case if the solutions are used hot or boiling. Even boiling water will have a marked effect in removing or loosening the various 65 matters attached to the fiber. The operation of retting and bleaching may also for some purposes be combined in one operation, a suitable chemical such as sodium peroxid being used for the purpose. The chemicals 70 to be used for the purpose of retting are principally the alkaline carbonates, bicarbonates, ammonia and a soap of one or more fatty acids, of colophony, or pine rosin, or a mixture of fatty acid soap and rosin soap. 75 To make the fiber less harsh, an emulsion of an oil, volatile or fatty, or of a fatty acid, such as kerosene, paraffin, rosin oil, turps, cotton or linseed oil, or red oil, which is the commercial form of oleic acid, may be used 80 to remove the extraneous or shive material 85 adhering to the fiber.

The chemical solutions are used either hot or cold. In the former case, they should be 90 weaker and the time of treatment will be correspondingly shortened and should generally not exceed four hours. The hot solution may be applied under pressure to hasten the operation. When flax material are treated in the cold, the operation may be 95 prolonged, even up to twenty-four hours and still render this process of retting economical. When the operation is carried on in the cold, the chemical action desired may be hastened by the use of pressure, hydrostatic 100 or pneumatic.

When rosin soap is used either alone or with another chemical, or with an emulsifying oil or fatty acid, it is preferably prepared at the place where it is to be used, by 105 simply dissolving caustic soda in water and adding thereto the requisite amount of rosin to form a translucent paste when hot.

After the retting operation has been finished the flax is washed, dried and subjected 110 to suitable mechanical manipulation to remove the loosened shive material. For this

purpose the flax may be passed through a suitable breaking machine, preferably one having much finer grooves or teeth than was used in the original breaking of the unretted flax stalks. In place of removing the shive material loosened through the operation of retting, by passing the retted flax through a breaking machine, as stated, this loosened material may also be removed by means of 10 scutching or beating machines, or by means of manual shive removing operations.

The fact that the retting period is shortened has also the advantage of a very considerable increase in the yield of flax 15 over ordinary processes where chemical retting is used as one of the important steps, as well as an increase in tensile strength.

The chemical solutions described may also be used successively in place of simultaneously or alternatively. Thus the flax material may be treated with an emulsion first, 20 and a peroxid solution afterward.

When an emulsion is used, it is preferable to prepare it as needed by means of any of 25 the ordinary emulsifying machines now in use.

What I claim as new is:

1. In the art of preparing linen fibers, the

improvement which consists in drying and breaking flax stalks, and subjecting the 30 broken material to the action of an aqueous liquid under pressure.

2. In the art of preparing linen fibers, the improvement which consists in drying and breaking flax stalks, and subjecting the 35 broken material to the action of an aqueous liquid under pressure at ordinary temperature.

3: In the art of preparing linen fibers, the improvement which consists in drying and 40 breaking flax stalks and subjecting the broken material to the action of an aqueous emulsion of soap and oil.

4. In the art of preparing linen fibers, the improvement which consists in drying and 45 breaking flax stalks and subjecting the broken material to the action of an aqueous emulsion of rosin soap and an oil.

Signed at New York in the county of New York and State of N. Y., this 18th day 50 of May, A. D. 1909.

GEORGE H. CAMPBELL
